UNITED STATES PATENT OFFICE.

HENRY W. WENZEL, OF PHILADELPHIA, PENNSYLVANIA, ASSIGNOR TO H. D. JUSTI & SON, OF PHILADELPHIA, PENNSYLVANIA, A FIRM COMPOSED OF HENRY D. JUSTI AND HENRY M. JUSTI.

ARTIFICIAL TOOTH.

1,245,843.

Specification of Letters Patent.

Patented Nov. 6, 1917.

Application filed July 28, 1917. Serial No. 183,277.

To all whom it may concern:

Be it known that I, HENRY W. WENZEL, a citizen of the United States, residing in the city and county of Philadelphia, State 5 of Pennsylvania, have invented a new and useful Artificial Tooth, of which the following is a specification.

My invention relates to an improvement in an artificial tooth more particularly 10 adapted to vulcanite work, and has for its object the elimination of metallic pins or other devices of the kind as means for attachment to the mouth plate, preventing the formation of air pockets heretofore existing 15 in such plates, as well as providing a strong connection for the tooth with said plate.

The invention is satisfactorily illustrated in the accompanying drawing, but the important instrumentalities thereof may be 20 varied, and so it is to be understood that the invention is not limited to the specific details shown and described, as long as they are within the spirit or scope of the claim.

Figure 1 represents a side elevation of an 25 artificial tooth embodying my invention.

Fig. 2 represents a plan view thereof.

Fig. 3 represents a transverse section on line 3—3 Fig. 1.

Fig. 4 represents a diagrammatic view of 30 a number of the teeth in position.

Similar numerals of reference indicate corresponding parts in the figures.

Referring to the drawings:—

1 designates an artificial tooth, the same 35 having thereon on the lingual side thereof the cervical ridge 2.

In the opposite sides of the tooth in the longitudinal direction thereof are the grooves 3 each of which exists between the rear wall 40 4 of the body of the tooth and the front wall 5 of the cervical ridge leaving between the latter and said body the neck 6 which is of reduced width and has in it the opening or vent 7 which extends transversely 45 therethrough.

The lower portion of said rear wall 40 of the body of the tooth is extended rearwardly forming the offsets 8 producing shoulders which project partly into the adjacent 50 portions of the grooves 3 toward the front wall of the cervical ridge, thus increasing the thickness of the rear portion of the body of the tooth at what may be termed the bases of said grooves above the biting 55 edge of the tooth below the opening 7, and

consequently strengthening said portions in proximity to said opening, thus compensating for any weakness that might be occasioned by said opening in the neck of the tooth.

It will be seen also that the walls of the grooves 3 are angular in the direction of their length, whereby the plate material will lie flat against the same, and the shoulders formed by the offsets 8 in said grooves will provide additional means for interlocking the tooth with the plate material and so forming a strong connection for said members, without the employment of metallic pins or other devices of the class.

Furthermore, in the process primarily of connecting the tooth with the plate, air is permitted to escape through the grooves 3 and opening or vent 7, thus preventing the formation of air pockets in the mouth plate 75 or tooth by the undercuts in the latter, said opening or vent also receiving some of the material of the mouth plate, which being anchored therein adds increased strength to the connection of the tooth with said plate 80 and vice versa.

I am aware that it is not new to form offsets or shoulders on the lower portions of the rear wall of the grooves in the sides of a tooth, the same projecting toward the front 85 walls of said grooves. This leaves said front walls of said grooves unobstructed to the extreme lower ends thereof, whereby the rubber or plate material occupying said grooves extends quite close to the biting 90 edge 9 of the tooth.

In the present construction, however, the portion of the rubber or plate material occupying said grooves will extend to the lower terminals of the rear walls of the offsets 8, 95 whereby a large extent of the rear of the biting portion of the tooth is left uncovered as at 10 for contact of the tongue, the advantages of which in the use of the tooth is evident. Then in the former construction 100 as the plate material extends from the rear offset to the biting edge of the tooth more of such material is required than when the material terminates at the base of the front offset as now located, hence there is a saving of the material in the present construction over the former one. In said former construction the plate material is imposed on the inner side of the portion of the tooth from the rear offset to the biting edge, hence 110

5 said portion necessarily thickens the tooth thereat as it is composed of both porcelain and plate material. This is avoided in my case, as the plate material terminates at the base of the front offset as now located and leaves the portion 10 of the rear of the tooth uncovered from the biting edge to said base of the front offset avoiding thickening of the tooth at and above the biting portion.

10 Having thus described my invention what I claim as new and desire to secure by Letters Patent, is:—

An artificial tooth formed of a body, a

cervical ridge and a reduced neck intermediate of said ridge and body, connecting the 15 same and having a groove in the side of said neck between said body and ridge, and an offset in said groove on the rear wall of said body, and projecting rearward from said wall partly into said groove toward the 20 front wall of said cervical ridge.

HENRY W. WENZEL.
